UNITED STATES PATENT OFFICE.

GEORGE H. ROBINSON, OF IDABEL, OKLAHOMA, ASSIGNOR OF ONE-HALF TO HARRY J. HALL, OF POPLAR BLUFF, MISSOURI.

AEROPLANE.

1,366,025.

Specification of Letters Patent.

Patented Jan. 18, 1921.

Application filed June 11, 1919. Serial No. 303,327.

To all whom it may concern:

Be it known that I, GEORGE H. ROBINSON, a citizen of the United States, residing at Idabel, in the county of McCurtain and State of Oklahoma, have invented certain new and useful Improvements in Aeroplanes, of which the following is a specification.

This invention relates to aeronautics, and 10 more especially to safety devices; and its primary object is to provide means on an aeroplane or other aerial ship for launching a parachute in times of emergency.

The invention consists of manually oper- 15 able means for dumping the aviator into the car of the parachute and automatically disengaging the car from its support.

The invention also consists in spring actuated means for ejecting the sail or top of 20 the parachute, which means are actuated by the fall of the car thereof.

The invention also consists in details as hereinafter more fully described and claimed, and as shown in the drawings.

Figure 1 is a side elevation of an aeroplane equipped with this invention.

Fig. 2 is a perspective view of the rocking seat.

Fig. 3 is a perspective view of the aero- 30 plane, showing the parts in position at the moment the parachute is thrown from the machine.

Fig. 4 is a side elevation of the parachute descending.

Figs. 5 and 6 are enlarged sectional views 35 of the spring gun for ejecting the sail of the parachute and

Fig. 7 is a perspective detail of the plunger thereof.

Fig. 8 is a cross sectional view through 40 the body of the aeroplane and the rocking seat.

Fig. 9 is an enlarged detail of the catch mechanism which prevents the seat from 45 rocking or tilting to dump the occupant.

Fig. 10 is a detail view of parts shown in Fig. 9.

I will say at starting that no details of 50 the aeroplane or air craft are necessary in connection with this invention excepting as described below, and I do not wish to be limited in this respect. In fact, while I have shown my invention as applied to a biplane, it might of course be attached to a car raised 55 by a gas bag, so long as the body of the car

had a seat which could be mounted on a pivot as described herein. Also I have set forth and illustrated my invention as applied to a two-seated machine, whereof the cadet is supposed to occupy the front seat 60 and the teacher or instructor the rear seat. In this case it is only the front seat which is hinged so it will tilt and means within reach of the instructor are provided whereby it can be unlatched and tilted to drop the 65 cadet in order to give him practice. It will be clear that my invention could be applied to both seats and tripped by the occupant of either, the car of the parachute underlying both seats so as to receive both men and convey them to safety. The primary object of 70 the invention is to mount the car of the parachute directly beneath the operator's seat, and in fact on guides carried by the seat itself from which it slips when the seat 75 tilts and the guides tilt; and also to mount the sail or top of the parachute within a spring gun or other ejector which is actuated by draft on a rope, pulled by the falling car.

The seat 1 within the body of the aero- 80 plane is shown as supported on a shaft 2 which is journaled in the sides of the body and the position of the shaft is such that the seat would tilt forward and dump the operator if it were not prevented. Upstand- 85 ing from one end of the shaft is an arm 3 connected by links 4 with levers 5 whose handles are near the operators so that they may tilt the seat if it does not act freely by itself. The arm is also connected by a rod 90

6 with a movable element or dog 7 whose nose 8 engages under a fixed hook 9 when the dog is drawn to the rear and the seat is in its normal position. This dog moves over a guide 10, whereon it may slide or above 95

which it may turn by means of twin links 11 as shown in Fig. 9, and pivoted to the dog is a catch 12 whose front end is free and adapted to drop into engagement with a stop 13 on the guide 10 when the dog is re- 100

tracted. A trip lever 15 pivoted to the body of the aeroplane (in the present illustration convenient to the instructor) is connected by a rod 16 with a lifter 17 within the guide and having a finger 18 underlying the catch 105

12; and therefore when said lever 15 is properly moved the finger lifts the catch so that its tip frees the stop 13. Now the weight of the cadet may be positioned to tilt the seat 1, or he or the instructor by 110

manipulating one of the levers 5 may cause the forcible shifting of this seat, but when it tilts the rod 6 pushes the dog 7 forward of necessity.

5 The tilting seat carries a pair of fingers 20 on which are slidably mounted hooks or eyes 21 which are carried at the sides of the car 22 of the parachute. The flooring of the aeroplane is omitted directly beneath 10 the seat as indicated in Fig. 3, and while the fingers 20 stand horizontal the car is retained thereon without the necessity for extraneous means. But when the seat tilts, it is obvious that the eyes will slide down the 15 fingers and the car drop as indicated in Fig. 3. The sail 23 of the parachute will be collapsed beneath the body of the machine as seen in Fig. 1 and will carry an eye or ring 24 at its apex removably engaged with the 20 tongue 25 of a gun or projector best shown in Figs. 5 and 6. As here illustrated a stout coiled spring 26 is mounted within a barrel 27 whose lower side constitutes the tongue, and is capable of being compressed by means 25 of a plunger 28 from which a rod 29 leads through the spring to an eye 30, to which latter is connected one end of a lever 31 pivoted at 32 on a suitable support within the body of the aeroplane. It is to be understood 30 that this spring ejector is put under tension before the machine leaves the ground, and therefore this lever need not be within reach of the pilot and is not shown in Fig. 1. From the eye 30 a rod 33 leads downward 35 and forward and is upturned at 34 into a latch engaging a notch 35 in the tongue 25, and a rope or cord 36 leads from this latch to the car 22 of the parachute as shown. When the spring is put under tension as 40 illustrated in Fig. 6, the latch 34 is pressed upward into the notch 35 to retain such tension. Now the ring or eye 24 at the top of the parachute is slid over the tip of the tongue 25 and against the plunger 28, and 45 thereafter whenever the cord or rope 36 is drawn upon suddenly the latch 34 is disengaged from the notch and the spring gun shoots the top of the parachute clear from the aircraft as seen in Fig. 3. If now care 50 is taken that the rope 36 is adjusted to proper length that the weight of the falling car 22 will give a jerk to the rope before the parachute turns out and weight is thrown onto its ring 24, it will be obvious that the 55 device will act without interruption. As above suggested, the tilting seat may be that of the forward operator, actuated by the rearward, or otherwise, and considerable latitude in this respect will be permitted.

60 The foregoing description and the drawings have reference to what may be considered the preferred, or approved form of my invention. It is to be understood that I may make such changes in construction and 65 arrangement and combination of parts, ma-

terials, dimensions, et cetera, as may prove expedient and fall within the scope of the appended claims.

Having thus fully described my invention, what I claim as new and desire to secure by Letters Patent is:—

1. In an aeroplane, the combination with a seat adapted to tilt forward, the floor of the aeroplane body being omitted beneath said seat, and forwardly projecting fingers 75 carried by said seat; of a parachute whose car has eyes slidably mounted on said fingers and whose sail has a ring, a tongue at the front end of the aircraft sustaining said ring, and latch mechanism for retaining 80 the seat against tilting.

2. In an aeroplane, the combination with a seat adapted to tilt forward, the floor of the aeroplane body being omitted beneath said seat, and forwardly projecting fingers 85 carried by said seat; of a parachute whose car has eyes slidably mounted on said fingers and whose sail has a ring, a tongue at the front end of the aircraft sustaining said ring, an arm connected with said seat 90 and moving forward as the seat tilts, a dog connected with the arm, a guide on which said dog moves, a catch for preventing its movement, and manually operable means for releasing said catch. 95

3. In an aeroplane, the combination with a seat adapted to tilt forward, the floor of the aeroplane body being omitted beneath said seat, and forwardly projecting fingers carried by said seat; of a parachute whose 100 car has eyes slidably mounted on said fingers and whose sail has a ring, a tongue at the front end of the aircraft sustaining said ring, an arm connected with said seat and moving forward as the seat tilts, a dog 105 connected with the arm, a guide on which said dog moves, a catch for preventing its movement, the catch being pivoted to the dog and with its free end adapted to engage a stop when the seat stands at normal, a finger 110 for raising the catch, and a hand lever connected with said finger, as described.

4. In an aeroplane, a tilting seat, the bottom of the plane being omitted beneath the seat, forwardly projecting fingers carried 115 by the seat and standing below the body of the plane, and manually operable mechanism for latching the seat against tilting; combined with a parachute whose car has eyes slidably mounted on said fingers and whose sail has a ring at its top, an ejector carried by the aircraft and with which said ring is engaged when the eyes rest on the fingers, and means for tripping said ejector by the fall of the car. 120

5. In an aeroplane, a tilting seat, the bottom of the plane being omitted beneath the seat, forwardly projecting fingers carried by the seat and standing below the body of the plane, and manually operable mecha- 130

- nism for latching the seat against tilting; combined with a parachute whose car has eyes slidably mounted on said fingers and whose sail has a ring at its top, an ejector 5 carried by the aircraft and with which said ring is engaged when the eyes rest on the fingers, latch mechanism for preventing the action of the ejector, and a rope leading from said latch to the car of the parachute 10 for tripping the latch mechanism and permitting the ejector to act as the car falls from said fingers.
6. In an aeroplane, the combination with a seat adapted to tilt forward, the bottom of 15 the body being omitted beneath said seat, and manually operable mechanism for preventing such tilting; of an ejector carried by the aircraft forward of such seat, latch mechanism for preventing its action, a para- 20 chute whose sail is provided with a ring at its apex adapted to be shot forward by the action of said ejector, means detachably connecting the parachute car with said seat so as to permit their disengagement when 25 the seat tilts, and means for actuating said ejector by the fall of said car.
7. In an aeroplane, the combination with a movable support for the pilot, a finger carried by said support, a parachute having 30 an eye slidably mounted on said finger and adapted to disengage the same when the support is moved, and a ring at the top of the sail of the parachute; of a spring gun carried by the aircraft forward of said 35 pilot's support and having a tongue with which said ring is adapted to be engaged when the gun is set, and mechanism for tripping the gun connected with the car of said parachute, as described.
- 40 8. In an aeroplane, the combination with a movable support for the pilot, a finger carried by said support, a parachute having an eye slidably mounted on said finger and adapted to disengage the same when the 45 support is moved, and a ring at the top of the sail of the parachute; of a spring gun

carried by the aircraft forward of said pilot's support and having a tongue with which said ring is adapted to be engaged when the gun is set, a rod connected with 50 the plunger of said gun and having a latch adapted to engage a notch in said tongue when the gun is set, and a rope connected with the free end of said rod and leading to the car of the parachute for tripping the 55 gun by the fall of said car.

9. In a safety device for aircraft, the combination with a tilting pilot's seat, a parachute, means for supporting the car of the parachute on the seat and automatically releasing it therefrom when said seat tilts, and manually operable means for preventing such tilting; of an ejector carried by the aircraft and with which the top of the sail of the parachute is connected, and means 60 65 for actuating said ejector, such means being connected with the car of the parachute and actuated by its descent.

10. In a safety device for aircraft, the combination with a seat, a parachute, means 70 for supporting the car of the parachute on the seat and automatically releasing therefrom when the position of said seat is changed, manually operable means for holding said seat in a set position against movement, and ejector means carried by the aircraft for actuating the parachute and releasing the same from said aircraft. 75

11. In combination with fuselage of an aeroplane, a car to receive the occupant, of 80 a parachute carried by the car, a seat releasably securing said car to the fuselage of an aeroplane, and releasable by said seat, and ejector means for releasing the parachute from the fuselage of the aeroplane. 85

In testimony whereof I affix my signature in presence of two witnesses.

GEORGE H. ROBINSON.
